(57) **CLAIM**

(22) Filed: **Dec. 4, 2000**

The ornamental design for a racing fuel can cigarette lighter,
as shown and described.

(51) **LOC (7) Cl. 27-05**

DESCRIPTION

(52) **U.S. Cl. D27/148**

FIG. 1 is a perspective view of the present invention.

(58) **Field of Search** D27/141, 148,
D27/154, 160; 431/129, 130, 132, 142-144,
151, 254-256, 267, 273, 274, 277

FIG. 2 is a top view of the present invention.

FIG. 3 is a bottom view of the present invention.

FIG. 4 is a right side view of the present invention.

FIG. 5 is a left side view of the present invention.

FIG. 6 is a front view of the present invention; and,

FIG. 7 is a back view of the present invention.

The broken lines are shown for illustrative purposes only
and form no part of the claimed design.
